STATION INDICATOR

Filed Feb. 17, 1926

Fig. 1.

Fig. 2.

A diagram of a mechanical assembly. On the left, the number '34' is written above the text 'Fig. 3.' which is enclosed in a bracket. To the right of the bracket is a coiled spring. A vertical line extends from the top of the spring to a horizontal bar. A small cylindrical component is attached to the horizontal bar below the spring. The number '35' is written above the spring. The numbers '37' and '39' are written below the spring, near the base of the vertical line.

UNITED STATES PATENT OFFICE.

EUGENE ALESSIO, OF NEW YORK, N. Y.

STATION INDICATOR.

Application filed February 17, 1926. Serial No. 33,886.

This invention relates to station indicators which are particularly designed for use on subways, street railways, or for other similar uses to give visual indication to passengers of the station being approached.

The invention particularly comprehends a station indicator for trains of cars by means of which an operator from a central controlling point may readily manipulate simultaneously the individual indicators in each car of the train.

The invention as a further object aims to provide a station indicator which is comparatively simple in construction and mode of operation, inexpensive to produce and install, and which is thoroughly reliable and highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Fig. 1 is a fragmentary cross sectional view through one car of a train, illustrating the same equipped with a station indicator constructed in accordance with the invention;

Fig. 2 is a sectional plan view of the indicator and diagrammatically illustrating the controlling means therefor;

Fig. 3 is a fragmentary detail view illustrating the motor controlling means in active operating position;

Fig. 4 is a similar view on a reduced scale illustrating the motor controlling means in a position to cut off the motor and effect the braking thereof.

Referring to the drawings by characters of reference, A designates a car having the usual clearstory roof construction providing the usual reduced upwardly projecting portion B. A casing or housing 10 extends transversely across the portion B, the opposite ends of which casing are open and register with openings C in the side walls D of the portion B. The casing 10 is provided with a window opening 11 medially of one of its vertical walls to expose a portion of a tape or strip 12 which is movable

through the casing and openings C. The opposite ends of the tape 12 are secured to and wound upon drums or reels 13 and 14 carried by vertical shafts 15 and 16 disposed exteriorly of the side walls D. The shafts are mounted in lower bearings 17 on the main roof of the car A and in upper bearings 18 within a housing 19 outside of the roof structure. Each shaft has secured thereto a bevel pinion 20 adjacent its lower bearing which meshes with a bevel gear 21.

The bevel gears are respectively secured to the motor shafts 22 and 23 of the motors 24 and 25 and the shafts 15 and 16 are driven in unison from the active motor by means of a sprocket and chain connection 26 and 27 between said shafts. The motor 24 has the opposite end 28 of its shaft 22 reduced and extending through a bearing opening 29 in a magnetically attractive element 30, which element is held against rotation by a key 31 engaging in a slot 32, allowing for axial sliding movement of said element on the reduced end 28 of the motor shaft. The free extremity of the reduced end 28 of the motor shaft is formed with a transverse head 33 which is turnable with the shaft in the cut-out portion 34 of the element 30 when properly aligned therewith. A spring 35 having its opposite ends respectively attached to the motor 24 and element 30 normally tends to dispose said element in a position to properly align the cutaway portion 34 with the head 33. The spring 35 also

functions to maintain in engagement, pairs of contact elements 36 and 37, and 38 and 39, carried, respectively, by and insulated from the element 30 and the motor 24. The element 30 is further provided with a recess 40 communicating with the cutaway portion 34 and adapted upon outward sliding movement of the element 30 to engage the transverse head 33 and brake the motor shaft against turning movement instantaneously. An electromagnet 41 is positioned in spaced relation to the outer end of the element 30 and is adapted when energized to attract said element 30 against the action of the spring 35 so as to simultaneously disengage the contacts 36 and 37 from the contacts 38 and 39, and engage the recess 40 with the transverse head 33. It is, of course, understood that the motors, reels, their shafts and connecting gears, the element 30 and its component parts, and electromagnet are housed by the housings 19.

From a suitable source of supply the positive current is fed through a feed wire 50 to the pivot 51 of the arm 52 of a double-throw, double-arm reversing knife switch, 5 through a branch wire 54 to a spring contact element 55 located within the casing 10 to bear against the lower edge of one face of the tape or strip 12. The opposed spring contact element 56 is arranged within the 10 casing opposite the contact 55 to bear against the opposite faces of the lower edge of the tape or strip, and said contact element 56 is connected by a conductor wire 57 to a similar spring contact element 58 within the casing 10. Another spring contact arm 59 is arranged within the casing opposite the spring contact 58 and said contact arm 59 is connected by a circuit wire 60 to one pole of the 20 electromagnet 41. The pairs of spring contact arms 55 and 56, and 58 and 59, are arranged adjacent the opposite ends of the window opening 11. The opposite pole of the electromagnet 41 is connected by a circuit wire 61 to the contact 62 of a switch 63, the pivot 64 of the switch arm 65 of which is connected by a circuit wire 66 to the negative pole of the source of supply. The switch 63 also includes a contact 67 which is 30 connected by a circuit wire 68 with the pivot 69 of the arm 70 of the reversing switch. At one end of its insulated base 71, the reversing switch is provided with contacts 72 and 73 and at its opposite end with contacts 35 74 and 75. The contact 72 is connected by a circuit wire 76 with one pole of the motor 24, the opposite pole of which is connected by a circuit wire 77 with the contact 39. The contact 38 is connected by a circuit 40 wire 78 with one pole of the motor 25 and is secured in parallel with the contact 39, the opposite pole of which motor 25 is connected by a circuit wire 79 with the contact 74. The contact 73 of the reversing switch is 45 connected by a circuit wire 80 with the contact 36 and the contact 37 is connected by a circuit wire 81 with the circuit wire 80.

The tape or strip 12 has printed or otherwise inscribed thereon longitudinally spaced indicia 82 representing the various stations on a given route, and said strip adjacent its lower end is provided with bridge elements 83 for bridging the spring contact arms, said 50 bridge elements 83 being located in spaced relation corresponding to the spaced relation of the pair of spring contact arms 55, 56, and 58, 59.

In use and operation, the conductor or 60 other operator of a train from a given control point where the switch 63 is located, throws the switch arm 65, the initial movement of which will engage the arm with the contact 67 which is preferably longer 65 than the contact 62. This closes the circuit

to the motor which has been previously rendered active by the reversing switch 71. As illustrated, the reversing switch is thrown to position to render the motor 24 active when the switch arm 65 engages the 70 contact 67. The current will flow from the positive pole of the source of supply through the circuit wire 50, thence through the wire 53, pivot 51, switch arm 52, the contact 72 of the reversing switch, the circuit wire 76, 75 through the motor 24, the circuit wire 77, the contacts 38 and 39, the contacts 37 and 36, the wires 81 and 80, the contact 73, switch arm 70, contact 69, circuit wire 68, contact 67 of the controlling switch, the switch arm 65, pivot 64, and the return circuit wire 66, to the negative pole of the source of supply. This initial movement of the switch permits the motor to move the tape or strip 12 in a direction from the reel or drum 14 to the reel or drum 13 so that the bridge elements 83 are disengaged from their bridging relation to the spring contact arms 55 and 56, and 58 and 59, prior to the engagement of the 90 switch arm 65 with the contact 62 of the controlling switch. The motor will continue to operate until the next pair of bridging elements 83 adjacent the following indicia 82 come into bridging relation with the 95 spring contact arms 55 and 56, and 58 and 59. When said bridge elements come into contact with the spring contact arms, it is obvious that the circuit to the electromagnet 41 will be completed, the current flowing 100 from the positive pole of the source of supply through the wire 50, the wire 54, the spring contact 55, the bridge element 83, the spring contact element 56, the circuit wire 57, the spring contact element 58, the bridge element 83, the spring contact element 59, the circuit wire 60 leading to one pole of the electromagnet, from the opposite pole of the electromagnet through the circuit wire 61, the contact 62 of the controlling switch, the switch arm 65, the pivot point 64, thence through the return wire 66 to the negative pole of the source of supply. Immediately upon completion of the circuit to the electromagnet 41 to energize the same, said magnet will attract the magnetically attractable element 30 which will break the motor circuit to the motor 24 and cause the recess 40 to engage with the transverse head 33 to instantaneously stop the motor shaft 22, thereby stopping the tape to expose the indicia in registry with the window opening 11 of the casing 10. When the signs have been changed, 110 the operator throws the switch arm 65 of the controlling switch out of contact with the contacts 62 and 67 so that the device is 120 ready for the next operation.

When the car or train is making a return 125

trip, the arms 52 and 70 of the reversing switch are swung from engagement with the contacts 72 and 73 into engagement with the contacts 74 and 75 so that the motor 25 will be actuated when the controlling switch is thrown to move the tape or strip 12 in a reverse direction.

It is of course understood that immediately upon the throwing of the switch arm 10 65 of the controlling switch out of contact with the contact element 62, the electromagnet will be de-energized and the spring 35 will effect a reverse movement of the element 30 so that the contacts 36 and 38, 15 and 37 and 39 will be re-energized and the recess 40 disengaged from its locking engagement with the transverse head 33 to dispose the cut-away portion 34 in alignment with the head 33, thereby allowing the same to 20 freely turn upon the next operation of the motor. It will be further appreciated that the motors 24 and 25 being coupled to move in unison, will cause the motor 25 when operating to turn the motor shaft 22 of the 25 motor 24 when the latter is idle.

What is claimed is:

1. In a station indicator, a strip having longitudinally spaced indicia thereon representing the various stations of a given route, 30 elements to which the opposite ends of the strip are secured and upon which the same are wound, a pair of motors having their shafts connected for rotation in unison and operatively connected with said elements, 35 said motors being selectively operable for driving said elements to move the strip in opposite directions, and means operable by the strip for automatically stopping the active motor and strip at predetermined 40 points.

2. In a station indicator, a strip having longitudinally spaced indicia thereon representing the various stations of a given route, 45 reels to which the opposite ends of the strip are secured and upon which the same are wound, a pair of motors having their shafts connected for rotation in unison and having operative connection with the reels, a circuit including said motors and a source of supply, 50 means in said circuit for selectively closing the circuit to either motor for moving the strip in opposite directions, a housing through which said strip is movable, said housing having a window opening for singly displaying the indicia therethrough, and means operable by the strip for rendering the motors inactive and stopping the strip to successively register the indicia with the window opening.

3. In a station indicator, a strip having longitudinally spaced indicia thereon representing the various stations of a given route, 55 reels to which the opposite ends of the strip are secured and upon which the same are wound, a pair of motors having their shafts

connected for rotation in unison and having operative connection with the reels, a circuit including said motors and a source of supply, means in said circuit for selectively closing the circuit to either motor for moving the strip in opposite directions, a housing through which said strip is movable, said housing having a window opening for singly displaying the indicia therethrough and means operable by the strip for rendering the motors inactive and stopping the strip to successively register the indicia with the window opening, said means including an independent circuit, an electromagnet in said circuit, an electromagnetically attractable element normally spaced from said electromagnet, a motor circuit-breaking means carried by said electromagnetically attractable element, and a motor stopping means carried by said element.

4. In a station indicator, a strip having longitudinally spaced indicia thereon representing the various stations of a given route, 60 reels to which the opposite ends of the strip are secured and upon which the same are wound, a pair of motors having their shafts connected for rotation in unison and having operative connection with the reels, a circuit including said motors and a source of supply, means in said circuit for selectively closing the circuit to either motor for moving the strip in opposite directions, a housing through which said strip is movable, said housing having a window opening for singly displaying the indicia therethrough, and means operable by the strip for rendering the motors inactive and stopping the strip to successively register the indicia with the window opening, said means including an independent circuit, an electromagnet in said circuit, an electromagnetically attractable element normally spaced from said electromagnet, a motor circuit-breaking means carried by said electromagnetically attractable element, and a motor stopping means carried by said element.

5. In a station indicator, a strip having longitudinally spaced indicia thereon arranged in proper order to represent the various stations of a given route, a casing having a window opening through which the strip is movable whereby sections of the strip are successively registered with the window opening to display the station indicating indicia therethrough, a pair of reels to which the strip is connected at its opposite ends for winding of the same from one reel to the other, an electric circuit including a pair of independent reel-driving motors having their shafts connected for rotation in unison, a source of power, a switch for selectively coupling the reel-driv-

ing motors in the circuit to move the strip in opposite directions, a second circuit including a source of supply, an electromagnet and a member attractable thereby when 5 the magnet is energized, a motor circuit maker and breaker operable by said member, a motor brake operable by said member, the said second circuit also including pairs of spaced spring contacts and bridge elements 10 therefor carried by the strip adapted to close said second circuit when the indicia registers with the window opening in the casing, and a common control switch for said circuits including means operable by 15 the switch to initially close the motor circuit for moving the strip a sufficient distance to break the second circuit prior to the subsequent closing of the second circuit by the final closing of the control switch where- 20 by said second circuit is subsequently closed when the next adjacent station-indicating indicia alines with the window opening.

6. A station indicator, including a strip having spaced station-indicating indicia 25 thereon, a casing through which the strip is movable, said casing having a window opening through which the station-indicating indicia is visible, electrically operable reversible mechanism for moving the strip 30 through the casing, a circuit including said mechanism, a reversing switch in said circuit, a normally closed circuit breaker in said circuit, a normally inactive braking means for said strip-driving mechanism, an 35 automatic electrically operable mechanism for stopping the strip as each successive station indicia-bearing portion of the strip registers with the window opening, said 40 strip-stopping mechanism including an independent secondary circuit, an electromagnet in said secondary circuit, a member attractable by said electromagnet when the same is energized, said member operatively 45 connected with the circuit breaker to open the same and operatively connected with the braking means to apply the same when

the electromagnet is energized and attracts said member, a normally open circuit-closing means in said secondary circuit, means carried by the strip for actuating said circuit-closing means when the station indicia-bearing portion of the strip registers with the window opening. 50

7. A station indicator, including a strip having spaced station-indicating indicia 55 thereon, a casing through which the strip is movable, said casing having a window opening through which the station-indicating indicia is visible, electrically operable reversible mechanism for moving the strip 60 through the casing, a circuit including said mechanism, a reversing switch in said circuit, a normally closed circuit breaker in said circuit, a normally inactive braking means for said strip-driving mechanism, an 65 automatic electrically operable mechanism for stopping the strip as each successive station indicia-bearing portion of the strip registers with the window opening, said strip-stopping mechanism including an 70 independent secondary circuit, an electromagnet in said secondary circuit, a member attractable by said electromagnet when the same is energized, said member operatively 75 connected with the circuit breaker to open the same and operatively connected with the braking means to apply the same when the electromagnet is energized and attracts said member, a normally open circuit-closing means in said secondary circuit, means carried by the strip for actuating said circuit-closing means when the station indicia-bearing portion of the strip registers with the window opening, and a common manually 80 operable control switch for both the said circuits, operable to close the first-mentioned circuit to initially move the strip for opening the strip controlled circuit-closing means prior to the closing of the secondary 85 circuit by the common control switch. 90
